UNITED STATES PATENT OFFICE.

MANUEL CARRANZA, OF HAVANA, CUBA.

DESIGN FOR A SPOON.

SPECIFICATION forming part of Design No. 21,257, dated December 22, 1891.

Application filed November 18, 1891. Serial No. 412,325. Term of patent 7 years.

To all whom it may concern:

Be it known that I, MANUEL CARRANZA, a citizen of Mexico, residing at Havana, Cuba, have invented and produced a new and original Design for a Spoon, of which the following is a specification, reference being had to the accompanying drawing, forming part thereof, which represents a spoon decorated in accordance with my design.

10 The main feature of the design consists in the formation of the upper or outer end of the handle, which is shaped to represent a matador or bull-fighter in appropriate costume and standing upon the head of a bull.

15 As an adjunctive feature the spoon-handle

beneath the representation of the bull's head is ornamented by a scroll, and beneath the scroll bars are represented as merging into the bowl of the spoon.

The bowl is represented as having artistically drawn thereon letters reading "Recuerdo Habana;" but such decoration I do not claim as a portion of the design.

I claim—

20 A design for a spoon, substantially as herein shown and described.

MANUEL CARRANZA.
